Primary Examiner — John R Yeh

(74) Attorney, Agent, or Firm — CANTOR COLBURN
LLP(57) **CLAIM**

The ornamental design for a squeegee, as shown and described.

DESCRIPTION

2. Squeegee

2.1 : Perspective (Top)

2.2 : Perspective (Bottom)

2.3 : Front

2.4 : Back

2.5 : Left

2.6 : Top

2.7 : Bottom

Right side view was omitted because it is a mirror image of the left side view; the parts colored in dark grey form no part of the claimed design.
